UNITED STATES PATENT OFFICE.

EDGAR B. HELFENSTEIN, OF LOS ANGELES, CALIFORNIA.

PAPER-PADDING APPARATUS.

1,273,781.

Specification of Letters Patent. Patented July 23, 1918.

Application filed July 11, 1916. Serial No. 108,589.

To all whom it may concern:

Be it known that I, EDGAR B. HELFENSTEIN, a citizen of the United States, residing at Los Angeles, in the county of Los Angeles and State of California, have invented new and useful Improvements in Paper-Padding Apparatus, of which the following is a specification.

This invention relates to a padding apparatus, and pertains especially to a device for stacking, compressing and padding printed sheets to form tablets.

The objects of this invention are, first, to provide a device having a stacker which 15 may be adjusted, so that the operations of placing sheets therein, jogging, measuring and drying the same, may be conveniently performed; second, to provide the apparatus with means convenient of adjustment 20 for compressing the stack formed; third, to provide the stacker with means to expose a side of the stack formed and compressed therein for gluing the same to form tablets; and fourth, to provide the stacker with 25 means for holding cord or other tying means, whereby the stacks may be formed in bundles without removing the same from the device.

I accomplish these objects by means of 30 the embodiment of my invention illustrated in the accompanying drawing, in which:

Figure 1 is a front elevation of the complete padding apparatus.

Fig. 2 is a plan view of the padding apparatus, with the stacker walls closed, and a hinge securing a stacker to the base.

Fig. 3 is a fragmentary perspective view showing a stacker in position for loading and jogging.

Fig. 4 is a fragmentary side elevation of the stacker showing the means of tying the stack.

Referring more particularly to the drawing, 5 indicates a bed preferably an iron plate of rectangular form, and having secured thereto at the ends stackers 6 and 7 in which the sheets to be padded are placed. Adjustably secured to the bed 5 is a press 8 arranged for compressing the stacks. Two 45 stackers 6 and 7 are shown duplicates of each other and one will be described.

The stacker 6 comprises a base plate 9 which is preferably of iron and is formed with channels 10 extending parallel to the 50 major axis of the bed when the stacker is

in an up-right position. Fixedly secured to the base plate 9 is a wall 11 and secured to the wall 11 by hinges 12 is a second wall 13, which may be swung outwardly exposing one side of a stack. Base plate 9 and 60 walls 11 and 13 form a trough.

Formed on the wall 11 are ribs 14 which are undercut on the inner faces for a purpose later described. A scale 15 is also formed on the wall 11 so that the height of 65 the stacks may be measured and by this means the position at which cardboard backs for the pads should be placed may be determined. The scale also serves to measure the height of the stack and thereby indicate the number of sheets therein. The stackers are pivotally secured to the bed 5 by hinges 16 with the pintles thereof disposed at 45° to the faces of the stackers, as shown in Fig. 2. The stacker may be swung 70 outwardly and into a position shown in dotted lines in Fig. 2, and in full lines in Fig. 3, whereby the stacker may be conveniently loaded.

A catch 17 is formed on the wall 13 for 80 locking the wall 13 to the base plate 9. This catch may be any convenient structure such as is well known.

Formed in the bed 5 intermediate the stacks is an aperture in which is slidably 85 mounted a post 18. The latter has notches 19 formed on oppositely disposed sides. Channels 20 are formed in the bed 5 communicating with the post aperture and arranged transverse to the axis of the latter. 90 A channel 21 communicates with channels 20 and is arranged transverse thereto. Mounted on each side of the post and within the channels 20 and 21 are angle pieces 23 forming catches. The catches 23 are arranged to slide transversely of the post 18 within the channels 20 and to engage with the notches 19. The channels 20 serve as guides to maintain the catches in alinement. A tension spring 24 is mounted intermediate catches 23 and tends to draw them toward each other into engagement with the post 18. When the catches 23 are disposed in notches 19 they lock the post 18 to the bed 5. In order to release the catches 23 100 I have pivotally mounted on the bed a cam 25 of such size and shape that when the handle 26 secured thereto is rotated, the ends of the cam will engage the catches 23 and force them out of the notches, thereby 105

110

releasing the post, and regulating the height of the vise suitable to the amount of stack to be compressed. When the cam 23 is moved into the position shown in Fig. 2, 5 the catches lock the post. Secured to the top of the post 18 by means of screw threads is a screw 27 which has mounted thereon a vise bar 28. A handle 29 is secured to the screw 27 for convenient operation of the 10 same. The vise bar 28 extends in opposite directions so that the ends are disposed above the stacks.

Blocks 30, one for each stack, shown in 15 Figs. 3 and 4, are provided. These blocks may be of various sizes depending upon the size of the sheets to be padded, and in practice three sets of blocks of various sizes, which by turning will fit the padding side of any stack, would be provided for a machine. The under surface of the blocks is provided with channels 31 and transverse thereto channels 32. Blocks 30 are placed 20 on the top of the stack and the vise bar 28 bears upon them in compressing the stacks.

25 In using the padding device the wall 13 is locked to the base plate 9 by means of the catch 17. The sheets to be stacked are divided into two equal piles. Stackers 6 and 7 are then swung outwardly to the position shown in Fig. 3. Ropes 33 for tying the stacks into bundles are placed in the channels 33 and in the channels formed between the ribs 14. The ribs being undercut on their inner faces, the ropes will lie 30 in the under-cuts, and are thus held in place. Sheets are then placed in the stacker and jogged to aline the edges. If it is desired to dry the same they are left in this position. The channels formed between ribs 35 14 in the wall 11 and the channels formed in the base plate 9 serve as ventilating ducts. When the sheets are dry, blocks 30 are placed in position. The ropes being disposed in channels 31 on the blocks bring 40 them into position as shown in Fig. 4 for cinching the same after the padding operation has been completed.

45 The stacker is now swung upwardly into an upright position as shown in Figs. 1 and 2. The post 18 is adjusted to a position such that the vise bar 28 is immediately above the stacks and the compression of the stack is produced by turning the screw 27 bringing the vise bar down upon 50 the top of the blocks. The catches 17 are then unlocked, thereby releasing the walls 13 which are swung outwardly exposing the front face of the stacks. The position of wall 13 when swung open is shown on the 55 right hand stack in Fig. 1. The glue is now applied to the exposed front face and the ropes 33 are cinched forming a compact bundle. The vise bar 28 may then be moved upwardly relieving the pressure and the 60 bundles removed, the pressure being main-

tained in the bundles by the ropes. They are thus held in shape for drying of the glue.

In order to prevent the ropes cutting into the sheets and mutilating the same, protectors may be used in coöperation with the ropes. These protectors are shown in Fig. 4 and indicated by the numeral 34. They comprise strips preferably of wood which are of a convenient size for insertion in the 70 slots 31 and 10 and have formed on one side a groove 35 within which the rope is 75 disposed.

80 It is obvious that I have provided an apparatus whereby sheets may be dried, jogged, stacked and measured with convenience, and whereby they may be padded and tied into bundles. The device has a large capacity by reason of the facility by 85 which the operations may be performed, and by reason of the tying of the stacks into bundles so that they may be removed from the device and dried.

What I claim is:

1. The combination of a bed, a stacker 90 mounted on said bed so that it may be swung from an upright to a horizontal position, and means for applying downward pressure to a stack of paper in said stacker, when the latter is disposed in an upright 95 position, said means being secured to said bed.

2. The combination of a bed, a stacker mounted on said bed so that it may be swung from an upright to a horizontal position, 100 said stacker comprising a pivotally mounted wall, and means for applying downward pressure to a stack of paper in said stacker when the latter is disposed in an upright position, said means being secured to said 105 bed.

3. The combination of a bed, a stacker secured thereto so that it may be swung from an upright to a horizontal position, 110 a post adjustably mounted in said bed, locking means for securing said post in selected positions, a screw mounted on said post, and a vise bar engaged by said screw for compressing a stack formed in said stacker.

4. The combination of a bed, a stacker secured thereto so that it may be swung from an upright to a horizontal position, 115 said stacker being provided with a wall movable to expose a face of a stack formed therein, a post adjustably mounted in said bed, locking means for securing said post in adjusted positions, a screw mounted on said post, and a vise bar engaged by said screw for compressing a stack formed in 120 said stacker.

5. The combination of a bed, stackers secured thereto at opposite ends, a post adjustably mounted on said bed intermediate 125 said stackers, said post formed with notches on opposite sides, catches slidably mounted 130

on said bed to engage said notches, means for moving said catches into and out of engagement with said notches, a screw mounted on said post, and a vise bar engaged by said screw and extending into a position above said stackers for compressing the stacks formed in said stackers.

6. In a paper padding device, the combination of a bed; a stacker hingedly secured thereto, so that it may be swung from a vertical to a horizontal position; and means mounted on said bed for applying downward pressure to a stack of paper in said stackers.

15 7. In a paper padding device, the combination of a bed; a stacker hingedly secured thereto, so that it may be swung from a vertical to a horizontal position; said stacker comprising a fixed wall, and a wall hinged 20 to said fixed wall.

8. In a paper padding device, the combination of a bed; a stacker hingedly secured thereto, so that it may be swung from a vertical to a horizontal position; said stacker

comprising a fixed wall, and a wall hinged 25 to said fixed wall; and means mounted on said bed for applying downward pressure to a stack of paper in said stacker.

9. In a paper padding device, the combination of a bed; a stacker hingedly secured 30 thereto, so that it may be swung from a vertical to a horizontal position; said stacker comprising a wall having longitudinally extending grooves formed therein.

10. In a paper padding device, the combination of a bed; a stacker hingedly secured 35 thereto, so that it may be swung from a vertical to a horizontal position, said stacker comprising a fixed wall and a wall hingedly secured to said fixed wall, and said stacker 40 having longitudinal grooves in a wall thereof; and means mounted on said bed for applying downward pressure to stacks of paper formed in said stacker.

In witness that I claim the foregoing I 45 have hereunto subscribed my name this 26th day of June, 1916.

EDGAR B. HELFENSTEIN.
